ATTORNEY

UNITED STATES PATENT OFFICE.

ROLLAND THOMPSON, OF NEW YORK, N. Y.

SAFETY CIGAR-HOLDER.

SPECIFICATION forming part of Letters Patent No. 888,625, dated October 1, 1901.

Application filed February 16, 1901. Serial No. 47,694. (No model.)

To all whom it may concern:

Be it known that I, ROLLAND THOMPSON, a citizen of the United States, and a resident of New York, in the county of New York and State of New York, have invented a certain new and useful Improvement in Safety Cigar-Holders, of which the following is a specification.

The object of this invention is to provide a safety cigar-holder which has several novel features; and it consists of an ordinary mouthpiece having therein a conical tube, the large end of which terminates near the open end of the holder and having an inturned annular knife-edge rim or flange, and the small end of the cone is either firmly secured or removably attached to a tube within the holder, the latter tube having a portion thereof projecting out into the cone, the principal features being to afford means whereby the nicotine from the cigar or the moisture from the mouth will be arrested at a point between the inlet of the tube and the mouth, so as to prevent injury from suction and also to enable the user to readily detach the cone or tube, or both, from the mouthpiece for cleaning purposes, as will now be set forth in detail.

In the accompanying drawings, Figure 1 is a longitudinal section of a mouthpiece equipped with my improved safety-holder; Figs. 2 and 3, modified forms of constructing the metallic parts forming the holder, and Fig. 4 another modified form.

The mouthpiece 4, usually termed "holder," is constructed in the usual form exteriorly; but the enlarged end is adapted within to receive a cone-shaped tube 5, the outer end of which terminates at a point near the enlarged end of the mouthpiece, where it is provided with an inturned annular rim or flange 6, which is brought to a knife-edge, so that when a cigar is pressed into the end the flange 6 will readily seize the cigar, and as the latter is more or less yielding the knife-edge will grasp the cigar and form a tight joint, thus assuring perfect draft. This cone, as shown in Fig. 1, rests snugly within the mouthpiece 4 and becomes, in effect, the holder of the cigar. In the body of the mouthpiece is a tube 7, having near its forward end an annular flaring flange 8, against

which the cone 5 rests when in position, so that a portion 9 of the tube 7 projects into the interior of the cone. The cigar (shown in dotted lines 10, Fig. 1) when placed into the holder has its cut-off end terminating near the end of the projection 9, so that any condensation or moisture will find its way into the space 11 around the projection 9.

In Fig. 2 the cone is shown attached directly to the tube 12, and this form is preferred where the cone and tube are permanently attached to each other. So in Fig. 3 the cone has a shank-like tubular stem 13 integral therewith, into which is inserted an inner tube 14, which has an end projecting into the cone. The tube 14 in this instance has its end closed, as at 15, and has one or more lateral openings 16, the object being to prevent any liability of having the end of the cigar come into direct contact with the ducts or inlets to the tube 14. It is obvious that these tubes and cones may be made permanent with the mouthpiece or detachable, the latter being preferable on account of the facility afforded in cleaning; but in either case any moisture which accumulates and once finds its way into the area between the end of the cigar and the projecting end of the tube must remain there and cannot pass down through the ducts 16 into the smoker's mouth.

Another very desirable form of making the cone and the tube connection is shown in Fig. 4, in which case the flaring or bell-shaped flange 8 has an exterior annular gain adapted to receive the core, so that the latter can readily be removed.

What I claim as new is—

1. A cigar-holder comprising a mouthpiece having therein a conical tube provided with an inturned annular rim or flange, and a duct or tube attached thereto, projecting into the cone, as set forth.

2. A cigar-holder comprising a mouthpiece, having therein a conical tube provided with an inturned annular rim or flange, a tube within the holder to which said cone is removably attached, and a projection from said tube which extends into the cone, as set forth.

3. A cigar-holder having a conical tube with an inturned annular edge for grasping the cigar, in combination with a tube which

projects into the cone, forming a chamber between the end of the cigar and the tube, as herein set forth.

4. A cigar-holder comprising a mouthpiece in combination with a conical tube having at its enlarged end an inturned annular edge, secured to a tube within the mouthpiece, said tube extending out into the conical tube, and communicating with the duct of the mouth-piece, said tube and conical piece being sep-

arable and removable from said mouthpiece, as set forth.

Signed at New York, in the county of New York and State of New York, this 8th day of February, A. D. 1901.

ROLLAND THOMPSON.
